UNITED STATES PATENT OFFICE.

HENRY W. RUBINKAM, OF CHICAGO, ILLINOIS.

AEROPLANE CONSTRUCTION.

1,319,117.

Specification of Letters Patent.

Patented Oct. 21, 1919.

Application filed February 14, 1919. Serial No. 277,014.

To all whom it may concern:

Be it known that I, HENRY W. RUBINKAM, a citizen of the United States, residing at Chicago, in the county of Cook and State 5 of Illinois, have invented certain new and useful Improvements in Aeroplane Constructions, of which the following is a specification.

The present invention has to do with 10 certain improvements in the stress members of aeroplanes and the like, particularly of the multiplane type, such as biplanes, etc. These stress members extend between the upper and lower wings or planes and join 15 them together in such manner that they will operate properly in unison. There are two sets of stresses to be taken care of in this connection, including the stresses of compression and those of tension. The com- 20 pression stresses are those which tend to carry the planes closer together, and the tension stresses are those which tend to separate the planes and move them farther apart.

In the past it has been customary to pro- 25 vide two sets of stress members for taking care of these two classes of stresses. The stresses of compression were taken care of by compression struts which perform prac- 30 tically no other function than to maintain the planes separated the proper distance. The tension stresses were taken care of by means of wire or cords extending between the two planes and which were entirely 35 separate and distinct from the compression struts. Since the resistance to the move- 40 ment of the machine through the air occa- sioned by the struts and wire is very large, it becomes very desirable to reduce their number and size as much as possible. The presence of a large number of tension wires 45 in addition to the compression struts has been very disadvantageous and very objectionable from the standpoint of power nec- essary to drive the machine through the air as well as from the standpoint of interfering with its control in flight.

The main object of the present invention is to improve the form and construction of the stress member in such a manner that the 50 stresses of tension and of compression can both be taken care of simultaneously, either directly or indirectly, and performing both the tension and compression functions.

Another object of the invention is to im- 55 prove the form and construction of the stress

members themselves and to improve the manner in which they are attached or connected to the ailerons or frame of the wings.

Another object of the invention has to do with the manner in which it is possible to 60 balance the tension produced throughout the system so as to equalize the tension in the various stress members, and so that the tension of the entire tension system can be 65 very readily and nicely adjusted.

Other objects and uses of the invention will appear from a detailed description of the same which consists in the features of construction and combinations of parts hereinafter described and claimed.

In the drawings:

Figure 1 shows a front view of the bi- 70 plane having applied thereto the features of the present invention;

Fig. 2 shows a longitudinal section through 75 a stress member embodying the features of the present invention, and shows the manner in which the same may be attached to the upper and lower wings;

Fig. 3 shows a cross section taken on the 80 line 3—3 of Fig. 2, looking in the direction of the arrows;

Fig. 4 shows a cross section taken on the line 4—4 of Fig. 2, looking in the direction 85 of the arrows; and

Figs. 5 and 6 show in detailed form a simple type of expansion block for use in securing the desired attachment on the tension members.

In the drawings I have illustrated a single 90 application of the features of the present invention to a bi-plane of simple form. It is to be understood, however, that in illustrating and describing this single embodiment of the features of invention, I do not in any 95 way intend to limit myself to the same except as I may do so in the claims.

Bearing the foregoing in mind, the machine illustrated includes the upper wings 7 and 8 and the lower wings 9 and 10, the body 100 11, propeller 12, gear 13, and such other apparatus as is customary in the construction of machines of this kind.

Extending between each pair of upper and lower planes, are the stress members designated in their entirety by the numeral 14. In the construction illustrated, the upper wings or planes are longer than the lower ones, and there are provided three stress members between each pair of planes, the 110

same extending in a zigzag fashion from a point on the lower wing adjacent to the body out to a point on the upper wing farthest removed therefrom.

5 Compression struts have been used in the past for insuring proper separation between the planes, and it has been quite customary to make the same hollow so as to lighten them without materially detracting from 10 their strength. It has, however, been held in the past to provide separate tension members in the form of steel cables or the like. These have been strung between the planes quite separate and distinct from the presence of the compression struts.

15 In carrying into effect one of the features of the present invention, I avail myself of the fact that the compression struts are sometimes made hollow so as to accommodate 20 therein the tension cables or members. The ends of the latter are then joined to the upper and lower planes in such manner that they will effectively take up the tension forces. In those cases in which it is customary 25 to provide a number of distinct compression struts, it is possible to pass the tension cables successively through a number of them, so that a common length of cable can be used for them all, in which case it is 30 only necessary to provide two points of anchor into the wings, thereby simplifying and improving the construction.

35 Referring again to the drawings, a simple form of the strut is illustrated in detail in Figs. 2 to 6 inclusive. It compresses a hollow shaft or bar generally of wood, its 40 end portions 15 and 16 being brought into suitable engagement with the upper and lower wings 17 and 18 respectively.

45 This strut 14 is generally of special cross section or contour, as shown in Figs. 3 and 4, so as to cause a minimum amount of wind resistance when traveling in the direction of the arrows adjacent to said figures.

50 It has in the past been customary to provide a longitudinal bore or passage 19 through each of these compression struts for the purpose of lightening it. According to the present invention, I pass a tension 55 cable 20 through the strut and join or connect it to the wings or planes in suitable manner. For this purpose I provide metal tubular anchors 21 and 22 in the end portion of the strut, which anchors extend over 60 and connect into the adjacent wings or planes. These tubular anchors serve not only to anchor the ends of the struts to the wings, but also being tubular serve to pass the cable through the wings, so that they can be joined or connected or anchored to them in the most convenient manner.

65 Where a number of stress members are used on each side of the machine as, for example, the arrangement shown in Fig. 1, the tension cable may be passed in succession

through the different members and have only its end portions anchored. For example, the left side cable, in Fig. 1, may have its outer end anchored at the point 23 and its inner end anchored at the point 24, and the right 70 side cable, in said figure, may have its outer end anchored at the point 25, and its inner end anchored at the point 26.

75 Where the cable passes from one stress member to another, it is conveniently passed clear through the framework or wings, as shown in Fig. 2, and over a suitable abutment block. This abutment block, designated in its entirety by the numeral 27, 80 serves not only to tie the framework to the stress members, but also serves to permit the tension cable to equalize its tension by sliding or moving a slight amount in either direction, as the case may be. A convenient form of such block is shown in detail in 85 Figs. 5 and 6. It comprises the two sections 28 and 29 which may be separated from each other a slight amount by means of a tapered screw 30 so as to raise the section 28, and thus pull up the cable so as to increase its 90 tension. Lugs or beads 31 and 32 are provided in the section 28 so as to guide the cable 20 over said section. The ends of the cable are conveniently anchored in any suitable manner as, for example, by the use of a 95 loop 33 on the end of the cable in conjunction with a turnbuckle 34, said turnbuckle having its inner ends anchored to the frame 100 of the machine.

I claim:

1. In an aeroplane of the plural wing type, the combination with the upper and lower wings, of a plurality of stress members extending in zigzag fashion between said wings, the end portions of consecutive stress members being in close proximity to each other, each stress member being provided with a longitudinal passageway, tubular anchors extending between the end portions of the stress members and the adjacent wings 110 and serving to anchor the ends of the stress members to the wings, a tension cable extending in succession through the several stress members and over the wings, means for anchoring the end portions of said tension cable to the wings, and expansion blocks located between the wings and the tension cable at the points where said cable passes between successive stress members, substantially as described.

115 2. In an aeroplane of the plural wing type, the combination with the wings thereof, of a plurality of stress members extending in zigzag fashion between the wings, the end portions of consecutive stress members being located relatively close together, the wings being provided with longitudinal passageways, means for anchoring the end portions of the stress members to the wings, a tension cable passing in succession through 120 125 130

the stress members and over the wings, and means for anchoring the end portions of the tension cable to the wings, substantially as described.

- 5 3. In an aeroplane of the plural wing type, the combination with the wings thereof, of a plurality of stress members extending between the wings in zigzag fashion, said stress members being provided with longitudinal 10 passageways, means for anchoring the end portions of the stress members to the wings, and a tension cable extending through the

successive stress members over the wings, substantially as described.

4. In an aeroplane of the plural wing type, 15 the combination with the wings thereof, of a plurality of stress members extending in zigzag fashion between the wings, said stress members being hollow, and a tension cable extending in succession through the stress 20 members and over the wings, substantially as described.

HENRY W. RUBINKAM.
